UNITED STATES PATENT OFFICE

163,667

CREAMER

Russel Wright, New York, N. Y.

Application December 13, 1950, Serial No. 13,411

Term of patent 7 years

(Cl. D44—21)

To all whom it may concern:

Be it known that I, Russel Wright, a citizen of the United States of America, and a resident of the city of New York, Borough of Manhattan, county of New York, and State of New York, have invented the new and original Design for a Creamer, of which the following is a specification, reference being had to the accompanying drawings, forming part thereof in which:

Fig. 1 is a top plan view of a creamer embodying my new design.

Fig. 2 is a side elevational view; and

Fig. 3 is a cross-sectional view thereof taken on line 3—3 of Fig. 1.

I claim:

The ornamental design for a creamer, as shown.

RUSSEL WRIGHT.
